PULL TOY

Ernest T. Frisk, Box 840, Hibbing, Minn.

Filed July 13, 1960, Ser. No. 61,346

Term of patent 7 years

(Cl. D34—15)

The figure is a perspective view of a pull toy showing my new design, the side opposite being substantially a mirror thereof.

I claim:

The ornamental design for a pull toy, as shown and described.
